UNITED STATES PATENT OFFICE.

WILLIAM R. LINDESEE, OF CHICAGO, ILLINOIS, ASSIGNOR TO FREDERICK Y. NICHOLS,
OF CHICAGO, ILLINOIS.

VALVE.

Specification of Letters Patent. Patented June 30, 1914.

1,101,643.

Application filed May 1, 1913. Serial No. 764,757.

To all whom it may concern:

Be it known that I, WILLIAM R. LINDESEE, a citizen of the United States, residing at Chicago, in the county of Cook and 5 State of Illinois, have invented certain new and useful Improvements in Valves, of which the following is a specification.

My invention relates to improvements in valve structures of that class wherein a 10 valve frame surrounds a guiding stud that projects from a valve seat structure and is adapted for reciprocable movement thereon and when raised is automatically returned to its normal position by means of a spring.

15 The salient features of my invention is the provision of means for readily and cheaply renewing the seating surfaces of said structure, so as to preserve the major portion of the structure for further continued use. In 20 valves of this character, the packing rings that are usually carried in the valve frame are generally renewable, but the structure carrying the coöperating valve seats is, in most instances, an integral part of the seat, 25 so that when the seats become worn by use the entire seat structure is thrown away, including, in many cases, the valve portion.

The object of my present invention is to 30 provide a new and improved means for inserting new seating rings in the old seat structure and to retain said rings therein by a very simple and effective expedient.

Other and further objects of my invention will become readily apparent to persons skilled in the art from a consideration 35 of the following description when taken in conjunction with the drawing, wherein—

Figure 1 is an elevation of a valve structure, showing the parts containing my invention in section, taken on line 1—1 of Fig. 2; Fig. 2 is a plan view of the seat-containing structure; Fig. 3 shows the relative position of the parts in section, before assembling; Fig. 4 is an enlarged plan view of 45 a portion of the seat-containing structure, showing the grooves or annular recesses for retaining the seat-ring; Fig. 5 is a portion of one of the seat rings.

In all the views the same reference characters are employed to indicate similar parts.

10 is the valve structure containing the usual packing rings surrounding a centrally disposed stud 11 which projects from the

seat structure 12. The valve 10 is held normally on its seat by means of the resilient spring 13 that is retained upon the studs 11 by the nuts 14 as usual in such constructions.

The valve seats comprise two annular portions or rings 15 and 16 that project a suitable distance above the upper surface of the valve-seat structure 12. These rings are usually integral parts of the structure 12 and when, after continued use, these rings 65 become worn so as to be no longer serviceable the entire seat structure 12 is usually cast aside and an entire new valve takes its place.

The salient feature of my invention is the means employed for substituting new rings 15 and 16 for those which constitute an integral portion of the structure 12, and to this end I turn into the upper surface of the seat structure 12 two annular recesses 17 and 18 70 and insert in these recesses rings 15 and 16 which in all essential respects are practically the same as the rings which were originally made as integral portions of the seat structure 12. After the rings 15 and 16 have been 80 inserted in their respective recesses 17 and 18, I drill two holes 19 and 20 in any of the arms 21 constituting the spider of the valve structure 12. Previous to inserting the rings 15 and 16 in their respective recesses, I turn 85 in either of their side surfaces grooves 22. The grooves 22, in each of the rings 15 and 16, confront the holes 19 and 20 in the spider arms 21. I now provide pins 23 and 24 having tapered heads. When the rings 15 and 90 16 are held firmly in their respective recesses, I then drive the pins 23 and 24 in the holes 19 and 20 respectively, in one or more of the arms or spokes 21. The act of driving the pins 23 and 24 in the holes causes portions 95 of the metal which is adjacent the respective rings, and which surrounds the said holes, to be set over, the tapered heads of the pins 23 and 24 corresponding substantially to the taper of the grooves 22 so that the 100 metal of the part 12 which is in the same plane with the axis of the pins and grooves 23 and 24 is set over into the grooves, as clearly shown in Fig. 1, rendering it practically impossible to remove the rings 15 and 105 16 from their positions with reference to the part 12, and firmly holding them in place.

If desired, more than one spoke 21 may be

treated in this way, as shown in Fig. 2, but in practice I have found that the treatment of a single spoke is sufficient.

If rings have previously been inserted in the part 12 and it is desired that new rings be inserted, the first inserted rings may be turned out of their respective grooves and new rings provided and other spokes in the structure may be perforated and pins 23 and 10 24 driven into the perforations; thus second or third set of rings may, in a similar manner, be inserted and retained in the seat structure 12, and by this means the major portion of the material constituting the 15 valve structure may well be retained and used for a relatively protracted length of time.

What I claim is:

1. A valve-seat structure comprising a 20 body-part having an annular recess therein to receive a valve-seating ring; a valve-seating ring having a groove in its side surface, contained within said annular recess when said ring is in place; and a tapered pin 25 driven into a perforation provided in the valve-seat structure near said groove, whereby to set over a part of the metal of said valve-seat structure into said groove to retain the ring in place.

2. A valve structure comprising a body- 30 part having an annular recess therein to receive a packing ring; a packing ring having a groove in its side surface, contained within said annular recess; a plurality of arms joining the said body part with a hub part; and a tapered pin driven into a perforation provided in one of the arms near said groove, whereby to set over a part of the metal into 35 said groove to retain the ring in place.

3. A valve structure comprising a peripheral ring joined to a hub part by a plurality of arms, the said peripheral ring and hub part having annular recesses therein to receive packing rings; packing rings each having a groove in its side surface adjacent the 45 other ring, contained within said annular recesses when said rings are in place; and a tapered pin driven into a perforation provided in one of the said arms; whereby to set over a part of the metal of said arm into 50 the grooves in the packing rings and to retain the same in place.

In testimony whereof I hereunto set my hand in the presence of two witnesses.

WILLIAM R. LINDELSEE.
